CORNER BASE CABINET CONSTRUCTION

Richard F. White, Salem, Ohio, assignor to Mullins Manufacturing Corporation, Salem, Ohio, a corporation of New York

Application December 6, 1940, Serial No. 368,831

1 Claim. (Cl. 312—142)

The invention relates to kitchen cabinet constructions, and more particularly to prefabricated kitchen cabinets designed to be installed as units to make up a completely modern kitchen.

In a modern kitchen compactness is essential as well as appearance, and consequently maximum top working surface must be provided with maximum storage space. In arrangements of cabinet units which fit around a room corner, a corner base cabinet is used to provide top working surface in the corner, but since there is no front exposed surface of the corner cabinet through which access can be had to the storage space below the top of the corner cabinet, this storage space is ordinarily wasted.

In specially built kitchens, access to the corner storage space is frequently had through the inside wall of one of the cabinets adjoining the corner cabinet, but in prefabricated cabinet units many and various sizes of base cabinets with both sides closed are required and numerous combinations of right and left hand cabinets fitting up to the corner cabinet are possible, so that it is impractical to provide base cabinets in all these sizes with one open side for matching an open side of the corner cabinet.

Moreover, it is awkward and inconvenient to reach through the door of one cabinet and through the side thereof into an adjoining cabinet, especially as articles stored in the one cabinet are usually in the way and must be moved.

It is therefore a general object of the present invention to provide, in an arrangement of prefabricated kitchen cabinet units, a novel corner base cabinet construction which gives maximum top working surface and accessible maximum storage space.

In a modern kitchen, wall cabinet units are located along the walls above the base cabinet units, and while the wall cabinet units are spaced above the base cabinet units to make the top surfaces of the latter available for working surface, still the wall cabinet units must be located at a minimum height so as to be easily accessible by a woman of average height reaching over the base cabinet units.

A specific object of the present invention is to provide a corner base cabinet having a novel and improved hinged top wall requiring minimum clearance for swinging open, so as to clear wall cabinets located an accessible distance above the corner base cabinet.

Another object is to provide a corner base cabinet having an improved hinged top wall with no

exposed handles or hinges so as to give maximum unobstructed top working surface.

A further object is to provide a corner base cabinet having a novel top wall hinged in such a way as to be partially counterbalanced when closed.

A still further object is to provide a corner base cabinet having an upwardly lifting top wall which swings clear of the adjoining cabinet and yet lies closely adjacent thereto along the lifting edge when closed.

And finally, it is an object of the present invention to provide a novel and improved corner base cabinet which embodies all of the foregoing objects in an extremely simple and inexpensive construction.

These and other objects are accomplished by the novel units, combinations and arrangements comprising the present invention which is shown by way of example in the accompanying drawings, and which is hereinafter described and defined in the appended claim.

The invention may be stated in general terms as including a corner base cabinet located between adjoining prefabricated cabinet units and having a top wall hinged on its under side at a position nearer its rear edge than its front exposed corner but spaced from and parallel to its rear edge, in such a way that the rear edge swings down into the cabinet space when the top wall is opened, the front corner of said top wall overlapping the cabinet corner wall to provide a finger grip for lifting said top wall.

Referring to the drawings,

Fig. 1 is a fragmentary perspective view of a modern kitchen containing a plurality of prefabricated wall and base cabinets arranged along two walls extending from a corner of the kitchen;

Fig. 2 is an enlarged fragmentary vertical sectional view through the corner base cabinet shown in Fig. 1, as on line 2—2, Fig. 4;

Fig. 3 is a fragmentary horizontal sectional view through the corner base cabinet and adjoining base cabinets, as on line 3—3, Fig. 2;

Fig. 4 is an enlarged plan view with parts broken away of the corner cabinet and adjoining base cabinets as on line 4—4, Fig. 2;

Fig. 5 is a fragmentary sectional view as on line 5—5, Fig. 4; and

Fig. 6 is a vertical sectional view through one wall of the room showing the corner base cabinet and the wall cabinet above the same in elevation.

Similar numerals refer to similar parts throughout the drawings.

The modern kitchen shown by way of ex-

ample in Fig. 1 has a plurality of base cabinets arranged along the adjoining walls 7 and 8 of the room, and a plurality of wall cabinets spaced above the base cabinets a sufficient distance to make the top surfaces of the base cabinets available for working space and yet having the wall cabinets easily accessible to a woman of average height standing on the floor and reaching over the base cabinets. The corner wall cabinet 9 abuts wall cabinet units 9a and 9b on walls 7 and 8 respectively, and is provided with a door 10 extending diagonally across the corner so as to gain access to the storage space within the corner wall cabinet 9.

This type of door is not objectionable in a corner wall cabinet because the greater depth of the base cabinets below the wall cabinets causes the base cabinets to extend out into the room beyond the wall cabinets, and the door 10 of the corner wall cabinet accordingly does not interfere with the floor space. However, this type of door in a corner base cabinet would materially reduce the floor space in the kitchen especially when the door is swung open. Moreover, such a corner base cabinet construction would reduce the accessibility of the corner and adjacent wall cabinets.

The corner base cabinet 11 is provided with a relatively narrow exposed beveled corner 12 so as to give maximum floor space, and consequently the exposed corner surface 12 does not provide sufficient room for giving access to the storage space within the corner base cabinet 11.

The corner base cabinet 11 abuts one side of an adjoining prefabricated base cabinet unit 13 on the wall 7, and abuts one side of an adjoining prefabricated base cabinet unit 14 on the wall 8 at right angles to the base cabinet 13. The cabinet 11 is provided with a top which is coplanar with the tops of base cabinets 13 and 14 so as to provide maximum top working surface, and the present invention provides means for gaining access to the storage space within the corner cabinet 11 without reaching in through the doors of either of cabinet units 13 and 14, which would require providing openings in the side walls of said cabinets matching openings in the adjoining side walls of the corner cabinet.

As shown in Fig. 3, the base cabinet units 13 and 14 have rearwardly extending flange portions 15 and 16 abutting the room walls 7 and 8 respectively, the base cabinet 13 having a side wall 17 abutting a side wall 18 of the corner base cabinet 11, and the base cabinet 14 having a side wall 19 abutting a side wall 20 of the corner base cabinet 11 at right angles to the side wall 18.

The corner base cabinet 11 is provided with rearwardly extending flange portions 21 similar to the flange portions 15 and 16 for abutting the side walls 7 and 8 respectively, and with rear walls 22 and 23 parallel to the side walls 18 and 20 respectively and extending along the room walls 7 and 8 respectively.

The front corner portion 12 between the cabinet walls 18 and 20 is exposed to the inside of the room and extends diagonally between the adjacent corners of the cabinets 13 and 14.

As best shown in Figs. 2 and 4, a top piece 24 fits over the top of corner base cabinet wall 23 and covers the space 24' between the room wall 7 and the wall 23, and a top piece 25 fits over the corner base cabinet wall 22 and covers the space 26 between the room wall 8 and the wall 22. The top pieces 24 and 25 are provided with downturned flange portions 27 as indicated in

Fig. 2 for abutting the room walls, and the top pieces 24 and 25 are coplanar with the tops of the adjoining base cabinets 13 and 14 and with the top of corner cabinet 11 so as to provide a continuous unobstructed top working surface.

Referring to Fig. 2, the cover or table top 11a for the corner cabinet 11 is constructed to match the tops of the adjoining base cabinets, and preferably includes a top working surface of linoleum or the like indicated at 28 supported on a horizontal sheet metal wall 28 having downwardly and inwardly extending flange portions 29 around its marginal edges. Channel shaped trim members 30 preferably fit over the flange portions 29 and are provided at their upper ends with inwardly extending securing flanges 31 for overlapping the marginal edges of the linoleum 27.

As shown in Fig. 2 the inwardly extending flanges or legs 32 at the lower ends of the trim members 30 are adapted to rest on the upper ends of the walls 18 and 20 of the corner base cabinet when the cover or table top is in closed position so that the top surfaces of the securing flanges 31 of the trim members are coplanar with the top surfaces of top pieces 24 and 25, and with the top surfaces of similar trim members on the adjoining base cabinets 13 and 14.

In order to provide for opening the table top cover 11a of the corner base cabinet 11 to gain access to the storage space within the cabinet, the table top cover is hinged at its under side on the cabinet to permit it to swing upwardly about an axis parallel to one of its rear walls. As shown in Figs. 2 and 3, a transverse vertical partition wall 33 is provided extending between the walls 18 and 22 parallel to walls 20 and 23 and having a horizontally extending bridge portion 34 at its top edge terminating in a downturned flange 35. As shown in Fig. 6, the vertical wall 33 extends downwardly a substantial distance and from its lower end a horizontal wall 36 extends rearwardly to the rear wall 23, forming a rectangular compartment extending between walls 18 and 22 and having an open end in the wall 18.

The wall 33 is spaced forwardly from rear wall 23 of corner base cabinet 11, but is considerably nearer to said rear wall 23 than it is to wall 20 which has the exposed corner 12 at its front edge.

Means for hinging the table top cover on the transverse wall 33 preferably includes spaced concealed hinges 37 secured at one end to the bridge portion 34 of transverse wall 33 and at their other ends to channel brackets 38 secured to the horizontal wall 28 of the table top cover. As shown in Fig. 2, angles 39 may be secured to the under side of the bridge portion 34 directly under the hinges 37, for reinforcing the bridge portion 34 at those points.

Referring to Fig. 5, the wall 12 of the exposed corner portion of corner cabinet 11 is bent inwardly at its upper end, as shown at 40 so that the beveled corner 41 of the table top cover 11a overlaps the same to provide a finger hold to permit raising the corner of the cover for lifting the same and swinging it about the hinges 37 in the manner indicated in Fig. 6.

As shown in Fig. 6 the wall cabinet 9a is spaced above the top of corner base cabinet 11 an accessible distance which is less than the depth from front to rear of cabinet 11, that is, from the exposed corner 12 to the rear wall 23. Accordingly, if the cover 11a were hinged at its

rear edge, it would interfere with the wall cabinet 9 when swung open. By locating the hinges 37 at points spaced outwardly from the rear wall of the cabinet, the rear end 42 of the cover swings down into the compartment formed by walls 33 and 36 and the front end 43 of the cover swings clear of the wall cabinet 9a as the cover is opened. The depth of the compartment formed between transverse wall 33 and rear wall 23 is sufficient to allow the rear end 42 of the cover to swing through at least 90° downwardly into said compartment, as shown in Fig. 6. Moreover, the rear end 42 of the cover engages the wall 33 in fully open position, so that the wall 33 acts as a stop to limit the opening movement of the cover.

Due to the location of the hinges 37 at points nearer the rear wall 23 of cabinet 11 than to the wall 20, the cover is substantially counterbalanced so that it tends to remain in closed position. Also, the location of the hinges 37 provides for the front edge of the cover to swing away from the wall 19 of adjoining cabinet unit 14 immediately on its initial opening movement, so that the cover can fit closely to the cabinet 14 without interfering with the same when it is swung open.

The improved construction and mounting of the cover 11a on the corner base cabinet 11 is simple and inexpensive and provides for quickly and easily gaining access to the storage space within the corner cabinet without requiring reaching in through the doors of adjoining cab-

inets; and the table top cover 11a has no exposed handles or hinges on its top surface so that it provides maximum unobstructed working surface.

Thus the invention provides a novel and improved corner base cabinet construction which can be used with standard prefabricated base cabinet units, and provides maximum top working surface with maximum storage space which is accessible without requiring specially constructed adjoining base cabinet units having open sides adjacent to the corner cabinet. Moreover, the novel corner base cabinet construction is accessible without impairing or interfering with the accessibility of wall cabinets located at a required minimum height above the base cabinets.

I claim:

20 A corner base cabinet for the corner of a room including two front side walls extending at right angles to each other from a cabinet front corner and two rear side walls parallel respectively to said front side walls, a partition wall in said cabinet parallel to one of said front walls and located nearer to the rear wall parallel thereto than to said front wall, a top cover on said cabinet, and concealed means hinging said top cover on said partition wall, the rear edge of said top cover being adapted to engage said partition wall for limiting opening movement of said top cover.

RICHARD F. WHITE.
